WAX THREAD SEWING MACHINE

John J. Sheehan and William P. Egan, Lynn,
Mass.

Application November 22, 1932, Serial No. 643,844

12 Claims. (Cl. 112—34)

The invention relates to improvements in sewing machines of the waxed thread type and more particularly to sewing machines of the McKay type for forming a chain stitch.

5 The object of the invention is to provide an improved sewing machine of the class referred to.

A feature of the invention consists of a friction device for the needle bar of the machine 10 which will hold it in position during the periods of dwell of the needle bar while other parts of the machine are operating.

15 A second feature consists of a novel device for operating the cast-off and determining its position.

20 A third feature consists of a tape-guiding device constituting part of the horn, which will hold a tape in position within the shoe during the stitching operation so that said tape is sewed to the inside of the inner sole, to reinforce the latter.

Other features of the invention are herein-after pointed out.

Referring to the drawings:

25 Figure 1 is a side elevation of a sewing machine constructed in accordance with this invention.

Figure 2 is a front elevation of the same.

30 Figure 3 is a section on line 3—3 of Fig. 1 showing how the motor and driving elements are supported.

Figure 4 is a front elevation of the sewing machine head.

35 Figure 5 is a detail in side elevation of part of the work feeding mechanism showing the adjusting device.

Figure 6 is a section on line 6—6 of Fig. 9.

Figure 7 is a detail in plan of the prime power element of the sewing mechanism.

40 Figure 8 is a side elevation of the sewing machine head.

Figure 9 is a longitudinal sectional view of the feeding and adjusting device shown in Figs. 5 and 6 taken on the line 9—9 of Fig. 4.

45 Figure 10 is a side elevation of the needle bar and a cast-off mechanism.

Figure 11 is a side elevation showing the needle bar in another position.

Figure 12 is a side view of the lower part of 50 the needle bar showing the cast-off mechanism.

Figure 13 is a section on line 13—13 of Fig. 12 showing the holding device for the cast-off bar.

Figure 14 is a front elevation of the lower portion of the needle bar showing the cast-off.

55 Figure 15 is a section on line 15—15 of Fig. 10

showing the friction devices for the needle bar.

Figure 16 is a section on line 16—16 of Fig. 10 showing the abutment for the friction device used on the needle bar.

Figure 17 is a section on line 17—17 of Fig. 10. 5

Figure 18 is a partial section on line 18—18 of Fig. 17.

Figure 19 is a section on line 19—19 of Figs. 10 and 17.

Figure 20 is a side elevation of the horn showing part of the driving mechanism for the thread whirl and also a tape-guiding device in position on said horn.

Figure 21 is a side elevation on larger scale of the upper end of the horn with its interior 15 exposed.

Figure 22 is a vertical sectional view of the upper portion of the horn showing the whirl mechanism for the thread and its relation to the tape-guiding device.

Figure 23 is a side elevation of a shoe with the horn and tape-guiding device in position therein.

Figure 24 shows the top of the horn and the tape-guiding device from another point of view.

Figure 25 is a plan view of the tape-guiding device on the top of the horn with the tape in position.

Figure 26 is a plan view, partly in section of the top of the horn with most of the tape-guiding device removed.

Figure 27 is a plan view of the top of the horn broken away to show the thread whirl.

The illustrated embodiment of the invention comprises an improved frame 10 comprising a base 11 and a head that is indicated generally at

35 12. On the frame 10 is a table 13 on which work and tools may be supported. Secured to the front of frame 10 adjacent to table 13 is a shoe-

40 supporting horn 14 which is free to rotate as the work is fed or guided to the needle during the sewing operation. Also secured to the front of the frame is a wax-pot 15 through which the thread 16 passes to be covered or saturated with wax to facilitate the sewing operation. The thread 16 is supplied from a spool 17 supported on

45 a shelf secured to the frame.

The construction of the frame is novel inasmuch as it is built to support the various mechanisms near the center of gravity of the machine so as to prevent destructive vibration from taking

50 place and also permit the essential floor space to be reduced to the minimum. The frame comprises metal flanges 18 and 19 connected by an integral central web 20.

The frame 10 is provided with a head plate 21

20

45

50

55

and motor shelf 22 integral therewith, the web 20 being formed with a hole 23 to accommodate the motor 24 which is placed on shelf 22 as near the center of gravity of the machine and the operating parts as possible in order to minimize vibrations and floor space required. By placing the motor 24 in this position as illustrated a countershaft 29 may be placed centrally in position directly beneath said motor which is one of the advantageous features of the invention.

The motor 24 is provided with a shaft 25 on which is mounted a pulley 26 connected by a belt 27 with a relatively large pulley 28 mounted on one end of countershaft 29. Shaft 29 is journaled in a pair of vertically adjustable self-aligning bearings 30 and 31. The bearings are cylindrical in form and are pivotally mounted on the trunnions 32 and 33.

The lower ends of the trunnions which are indicated by the numerals 34 and 35 are mounted in vertical sockets formed in the base portion of the frame which allows said trunnions to be adjusted vertically and held in adjusted position by set screws. By this construction the bearings are placed centrally in relation to the frame as viewed in Fig. 1 and set up in alignment so as to receive the countershaft 29 and support the same in a position parallel with the motor shaft 25.

Fixed on the opposite end of the shaft 29 is a fly-wheel 36, Figs. 1 and 2, constructed to serve as one member of a friction clutch whose adjustable member is operated by one arm of a lever 37 which is fulcrumed on an arm 38 integral with the fixed trunnion 33.

This clutch mechanism is of usual construction and is operated by a foot lever or pedal, not shown, connected with the other arm of lever 37. When this arm of lever 37 is swung downwardly the clutch is set and when the lever 37 is freed the clutch is unset. The adjustable member of the clutch is loosely mounted on shaft 29 and is made with a pulley 39 around which extends a belt 40 for driving the pulley-wheel 41 of the sewing machine when the clutch is set, said belt being controlled by a belt-tightener 42. The wheel 41 is mounted on a shaft 43—44, Figs. 4, 7 and 8, carrying a gear 45, crank 46 and cam 47.

These parts 43—44, 45, 46 and 47 are made in one piece and are the prime controlling members to operate the machine in definite time relation, and with the novel adjustments on the various members are a great advantage over the devices used on other types of machines.

The shaft 43—44 is mounted in bearings 49 formed integral with vertical columns 50 and 51 which are supported by the head plate 21 forming part of the frame.

Secured to the upper ends of the columns is a top plate 52 which, with the head plate 21, forms an inclosure in which the operating members are located. The plate 52 is also held in position on the head plate 21 by other posts so that the plates can withstand the various operating stresses to which they are subjected.

The shaft 43—44 is rigidly connected with the parts 45, 46 and 47 which are formed integral and by this construction all of said parts are always in timed relation with one another and with the other moving parts of the mechanism. If the prime driving members should get out of time relation, it would destroy the working operation of the machine, and by arranging them as a unit, these members will always be in a pre-

determined position to facilitate the operation and maintenance of the machine.

The gear 45 drives a pinion 54, Fig. 8, mounted on a shaft 53 which runs in a bearing secured to the head plate 21. Shaft 53 is connected with and drives the mechanism for twirling the thread around the needle when the latter enters the horn thereby to form a sewing loop of a chain stitch, said connection including shafts 50 and 51, Fig. 1, and miter gears 58 and 59.

Gear 58 is fast on the lower end of a shaft 60, Fig. 20, mounted in bearings provided in the horn support 61. The shaft 60 which carries gear 58 acts through a train of gearing 57, shaft 56, and beveled gears 55, to drive a shaft 62 whose upper end is formed as a beveled gear 63 which meshes with the beveled gear 64 of the thread whirl. The beveled gears 63 and 64 operate in a chamber 65 formed in the top of the horn 14.

The chamber 65 is provided with a cover plate 66 which also serves as a support for the shoe during the sewing operation. The shaft 62 with the gear 63 and the whirl gear 64 have bearings in the horn and are so constructed and operated as to allow the whirl gear 64 to rotate in definite timed relation to the reciprocatory movements of a needle 67, and thread 16 is looped around the needle as usual. The gear 64 is provided with a supporting shoulder 69 and rotates in a bearing formed in the horn.

Formed in the beveled gear 64 is the needle hole 70 and an eccentrically disposed thread hole 71. The needle 67 occupies the exact center of gear 64 when the whirl loops the thread around it and is free to move axially into and out of the gear during the sewing operation.

As the hole 71 rotates carrying the thread 16 with it, it causes the thread to loop around the needle above the hook of the latter and said loop is drawn up through the work by the needle to form a stitch. The cover plate 66 is provided with a hole 72 which allows the needle to pass through in an axial direction and also serves for another purpose which will be taken up hereinafter. In machines of this kind plates 21 and 52 are provided with fixed bearings in which the moving devices of the stitch-forming mechanism are adapted to slide or move in performing the sewing operation. The needle 67 is held in a needle bar 74, Fig. 4, which has a reciprocating movement in the head plates 21 and 52 and is provided with a novel friction device which is one of the features of the invention.

In the operation of the machine it is necessary to hold the work or shoe in position on the horn. This is accomplished by a presser foot device operated by a cam on one face of gear 45 acting through a lever 75, Figs. 4 and 8. The presser foot 78 is carried by the presser bar 76—77 which is arranged to move vertically through plates 21 and 52, the presser foot and its bar being yieldingly urged downwardly by a coiled spring 80 whose lower end bears against a collar 82 on section 76 of the bar and the latter is adapted to be lifted by a hand lever 83 to insert or remove the work and at times is lifted automatically by lever 75.

Secured to the lower end portion 77 of the presser bar is a plate 84 having formed therein a cam slot 92 and adjacent to this plate is the feed lever 86. This lever is adapted to slide and swing within a groove of the end portion 77 as indicated by dotted lines in Fig. 4 and is mounted for oscillation and endwise movement upon a stud 89 on the presser-bar and engaging the 75

upper forked end 88 of the feed lever 86, the lower portion of the said lever carrying the feed foot 90 being thus adapted to move vertically and swing pivotally on the stud 89. To effect these feeding movements a link 91 is pivoted at 87 to the lever 86, said pivot pin 87 extending through the cam slot 92 in the plate 84.

To operate the feed lever 86 mechanism is used which includes the cam 47, Fig. 7, having a cam slot cut in its periphery which co-operates with a roll 94 carried by rocker arm 95, Fig. 9. The rocker arm 95 forms a part of a sleeve 96 which rocks on a fixed shaft 97.

The shaft 97 is mounted rigidly in bearings 98 and 99 forming a part of a bracket 100 which is bolted to the head plate 21. Rigidly secured to the bearing 99 by a set screw is a spindle 101 to which is also fastened a downwardly extending arm 102 which is held rigidly in position thereon by a set screw. Adjustably secured to the sleeve 96 is an arm 103 to the upper end of which is connected one end of a rod 104, Fig. 4, extending transversely across the machine and having its opposite end loosely connected to the ratchet lever 105 for locking and releasing the presser foot bar that holds the work in position.

Formed integral with the arm 103 is a boss 106 in which is fixed a spindle 107 on which a feed lever 108 is pivotally secured.

The adjustable connection between arm 102 and the feed lever 108 which is connected by link 91 with feeder 86 constitutes one of the features of the invention by which the movements of the shoe on the horn are varied thereby to vary the length of the stitch.

To obtain a maximum range of adjustment as shown on the drawings, Figs. 4, 5, 6, and 8, the arm 102 is provided with a slot 109 within which a block 110 is fixed with provision for adjustment by means of a pintle bolt 111 on which is swivelly mounted a block 114 slidably arranged within a slot 115 formed in the feed lever 108. By adjustment of the nut 116 the bolt 111 is loosened which allows the block 110 to be moved up or down as required, but normally the nut 116 and a washer 112 grip the arm 102 which holds the block 110 in a fixed position on arm 102 and allows the feed lever 108 to be vibrated on bolt 111 by arm 103. When the slot in the cam 47 rocks arms 95 and 103 and imparts a swinging movement to the feed lever 108, the latter acts through link 91, Fig. 4, to operate feed member 86.

The needle bar 74 is operated by the crank 46, Fig. 7, acting through a crank-embracing eccentric strap 117, pitman 118, walking beam 119 and link 129, Figs. 7 and 8.

The function of the walking beam 119 is to operate the needle bar 74 and to measure the thread 16. The crank 46 causes the walking beam 119 to swing on a pin 120 in a yoke 121, secured to the upper end of a slide-bar or rod 122 and at times during the operation of the mechanism this rod has imparted to it an end-wise reciprocating movement to control the measurement of the thread. Mounted on the rod 122 are two stop collars 123 and 124 which limit its movement in each direction according to the thickness of the material to be sewed. In Fig. 8, the needle is at the limit of its down stroke and inside the horn. As the crank 46 raises the needle quickly from the work the cast-off is caused to take its place over the hook of the needle to hold the thread in position therein during the upward movement of the needle as presently described.

During the downward movement of crank 46,

Fig. 7, the rod 122 is moved downwardly by beam 119, Fig. 8, until the stop 124 comes in contact with the member 127, Fig. 4, of suitable thread controlling or measuring mechanism which member rests on the section 77 of the presser bar. As the crank 46 completes this downward movement it acts through the pitman 118 and walking beam 119 to raise the needle bar while the rod 122 is held against downward movement by the engagement of stop 124 with the member 127.

When the crank 46, Fig. 7, swings upwardly it acts through the pitman 118, Fig. 8, to swing walking beam 119 in a direction to lift the rod 122 until the stop 123 engages the under side of the top plate 52. During this upward movement of rod 122 the needle bar is held at the limit of its upward movement by the friction device shown in Figs. 10 and 15. After the stop 123 comes into engagement with the top plate 52 continued upward movement of crank 46 and pitman 118 acts through the walking beam 119 to force the needle bar downwardly, said needle bar then sliding through the friction device shown in Fig. 15.

The lower end of link 129 is pivotally secured to an adjustable sleeve 133 secured rigidly to the needle bar 74 while the upper end of link 129 is pivoted at 125 to the walking beam 119. The needle 67 is provided with a hook 131, Fig. 14, which receives the thread to form the loop in the stitch and is carried upwardly by the movement of the needle bar 74. As the needle moves upwardly from the work the loop of thread in its hook is held in position within the same by a cast-off rod 132 which causes the preceding loop to be shed from the needle. In the operation of the needle bar there are periods of hesitation in its reciprocating movement, which requires that the needle bar 74 be restrained at times to cause it to remain at rest while some of the other operations of the machine are taking place and at the same time be free to move when sufficient power is applied to complete its movements. This is the purpose of the friction device of Fig. 15.

Alongside of and parallel with the needle bar is a post 134, Figs. 10 and 16, fixed rigidly at its opposite ends to the plates 21 and 52. Secured to the post 134 is a retaining clamp formed in two parts 135 and 136, Fig. 16, which are clamped rigidly to the post 134 by means of a bolt 137. The ends of these two parts that embrace the needle bar are provided with a clearance 138 as shown in Fig. 16 which allows the needle bar to move freely through the clamp. Located between the top plate 52 and the clamping members 135 and 136 is a friction device which causes the needle bar to dwell momentarily at each end of its stroke. The friction device referred to is a pincers structure made of two lever clamping members 139 and 140 having arms 141 and 142, respectively, which are connected by a spring 143 that is under tension so that arms 139 and 140 continuously grip the needle bar and so that at times the latter is held at rest while certain other functions are performed but so that the frictional grip of the pincers can be overcome when sufficient power is applied to the needle bar.

The vertical reciprocating movement of the needle bar 74 controls the cast-off 132. This is accomplished by novel mechanism including a bracket 151, Figs. 10, 11, 17 and 18, which is a rigid part of post 134 and has a hole therein adapted to receive a plunger 146. The outer end of this plunger is V-shaped and is adapted to engage a roll 147 carried by a bracket 148 which

is free to move axially on the needle bar 14. The plunger 146, is at times moved in bracket 151 in one direction by the roll 147 and at other times in the opposite direction by a compression spring 149.

The inner end portion of the plunger 146 is formed with a flat side portion as shown at 150, Fig. 19, that is slidably engaged with a complementary flat surface within the hole of bracket 151 to hold the plunger against rotative displacement. The plunger is free to move axially but is restrained from rotating by the bracket 151 as described. When the needle bar moves downwardly into the position shown in Fig. 10 the roll 147 is below the outer beveled end of plunger 146 and the needle is through the work. As the needle and needle bar move upwardly the bracket 148 is bunted past plunger 146 by a collar 133 fast on the needle bar and as the needle bar descends it is bunted past plunger 146 in the opposite direction by the sleeve 130.

At the start of the upward movement of the needle bar the needle and cast-off occupy the positions shown in Fig. 14 but as the needle withdraws from the work the upward movement of the cast-off is arrested until the hook of the needle is covered whereupon the collar 133 bunts the bracket 148 past plunger 146. At the start of the downward movement of the needle bar the downward movement of the cast-off is arrested until the hook of the needle is uncovered whereupon the bracket 148 is bunted past plunger 146 by sleeve 130.

The cast-off is fastened to the bracket 148 by a bolt 158, Fig. 13, having a transverse hole 154 formed through its shank adapted to receive the upper end of the cast-off rod 132. The bolt 158 extends through a hole in the bracket 148 and the cast-off rod 132 is clamped against the inside 40 of the bracket 148 by means of a nut 157 on bolt 158. Adjacent to bracket 148 the needle bar is recessed or cut away to accommodate the inner end of bolt 158 and permit longitudinal movement thereof and this recess communicates with 45 a longitudinal groove 155 in which the cast-off rod 132 is slidably mounted. A collar 144 fixed in position upon the lower end of the needle bar 14 holds the cast-off rod within groove 155.

When the inner sole of the shoe is broken, 50 or without sufficient strength to support the sewing, a reenforcing member is provided in the nature of a tape 145 fed from a suitable source into a guide 160, Figs. 20 to 26, while the horn 14 is inside the shoe during the sewing operation. 55 This tape reenforces the inner sole sufficiently to hold the sewing and save the shoe. As the horn 14 is free to rotate the tape guide must always remain in a fixed position relatively to the direction of feed independent of the movement of the horn. The guide 159 is made with 60 a bottom wall 160 and parallel inturned oppositely disposed side walls 161 and 162 which guide the tape as it is sewed to the inner face of the innersole of the shoe. To prevent the 65 tape guide from turning during the rotation of the horn, it is rotatably mounted on the horn directly in line with the needle. To allow the needle to pass through the guide, a hole 163 is provided through the latter which is extended 70 into a skirt 164 which under-laps the side wall of the hole 72 in the cover plate 66 of the horn through which the needle is free to pass. By this construction the tape guide can be positioned axially in line with the needle and loosely 75 fitted in the horn thus allowing the tape to be

sewed to the sole of the shoe and permitting the guide to be held against rotating relatively to the shoe by the tension on the tape and by the frictional engagement between the guide and innersole.

What we claim as new and desire to secure by Letter Patent in the United States is:—

1. A sewing machine having, in combination, a work support; a needle bar equipped with a needle and reciprocable toward and from said work support, and means for reciprocating said needle bar so as to cause it to dwell at the limit of its movement toward and from said work support for a predetermined length of time, said means comprising a walking beam whereof one 15 arm is connected with said needle bar, a vertically movable support for the fulcrum of said walking beam, stops to limit the movement of said support in each direction independently of the work support, and driving mechanism connected with the other arm of said walking beam for vibrating the latter to cause it to alternately reciprocate said needle bar and said support.

2. A sewing machine having, in combination, a work support; a needle bar equipped with a 25 needle and reciprocable toward and from said work support; means for reciprocating said needle bar so as to cause it to dwell at the limit of its movement toward and from said work support for a predetermined length of time, said means 30 comprising a walking beam whereof one arm is connected with said needle bar, a vertically movable support for the fulcrum of said walking beam, stops to limit the movement of said support in each direction; driving mechanism connected with the other arm of said walking beam for vibrating the latter to cause it to alternately reciprocate said needle bar and said support, and a friction device engaging said needle bar to 35 yieldingly oppose movement thereof.

3. A sewing machine constructed in accordance with claim 2 wherein said friction device consists of a pair of pincer-like lever arms embracing said needle bar and a spring connecting said lever arms so as to cause the latter to frictionally grip the needle bar.

4. A sewing machine having, in combination, a work support; a needle bar equipped with a needle and reciprocable toward and from said work support and means for reciprocating said needle bar so as to cause it to dwell at the limit of its movement toward and from said work support for a predetermined length of time, said means comprising a walking beam whereof one arm is connected with said needle bar, a vertically movable support for the fulcrum of said walking beam, stops to limit the movement of said support in each direction, a continuously 55 rotating driving element connected with the other arm of said walking beam for vibrating the latter 60 to cause it to alternately reciprocate said needle bar and said support, and means for frictionally and yieldingly opposing movement of said needle bar under the influence of said walking beam.

5. A sewing machine constructed in accordance with claim 4 wherein said frictional means comprises a pair of relatively crossed pincer-like lever arms having proximate end portions embracing and frictionally engaging said needle bar at opposite sides thereof and including a 70 spring under tension connecting said proximate end portions so as to hold the latter against said needle bar, the opposite proximate end portions of said lever arms embracing a fixed portion of the frame of the machine.

6. A sewing machine constructed in accordance with claim 4 wherein said frictional means comprises a pair of crossed pincer-like lever arms having proximate end portions embracing and frictionally engaging said needle bar at opposite sides thereof and including a spring under tension connecting said proximate end portions so as to hold the latter against said needle bar, the opposite end portions of said lever arms embracing a fixed portion of the frame of the machine, and also including abutments on the frame of the machine for holding said pincer-like lever arms against movement with the needle bar when the latter is reciprocated.
- 15 7. A sewing machine of the character described having, in combination, a work support; a needle bar carrying a needle and reciprocable toward and from said work support; a cast-off slidably and frictionally mounted on said needle bar so that it can slide relatively thereto to a limited extent; a spring pressed plunger disposed in the path of a portion of said cast-off past which said portion is moved when said cast-off moves with said needle bar, said spring pressed plunger engaging said portion during each stroke of the needle bar thereby to adjust the cast-off relatively to the needle bar in timed relation with respect to the movements of the needle into and out of the work.
- 20 8. In a sewing machine of the character described in combination, a horn for supporting the shoe; a needle bar equipped with a needle and reciprocable toward and from said horn; a thread whirl within said horn for looping the thread

around said needle; means for operating said whirl, and means on the top of said horn for guiding an innersole reenforcing tape into position to be sewed to the lowermost side of the innersole of the shoe as the sewing operation progresses.

5 9. A sewing machine of the character described constructed in accordance with claim 8 wherein said last-mentioned means consists of a tape guide mounted upon the top of said horn.

10 10. A sewing machine of the character described constructed in accordance with claim 8 wherein said last-mentioned means consists of a tape guiding member rotatively mounted upon the top of said horn so as to turn on an axis 15 approximately coincident with the axis of the needle when the latter is projected into the work, said guide being formed with a needle aperture coincident with said axis.

15 11. A machine of the character described having in combination a horn for supporting a shoe; a thread looping whirl rotatably mounted within said horn; means for operating said whirl, and a guide on the top of said horn for directing an innersole reenforcing tape into the path of said 20 needle between said whirl and the lowermost side of the innersole.

25 12. A sewing machine of the character described constructed in accordance with claim 11 wherein said tape guide is made with a needle 30 aperture surrounded by a sleeve that is rotatably mounted in the needle hole of the horn.

JOHN J. SHEEHAN.

WILLIAM P. EGAN.
